CLAIM

The ornamental design for a supple impact simulated folding chair, substantially as shown and described.

DESCRIPTION

FIG. 1 is a perspective view of a supple impact simulated folding chair in accordance with the present invention.

FIG. 2 is a front view thereof.

FIG. 3 is a rear view thereof.

FIG. 4 is a left side view thereof.

FIG. 5 is a right side view thereof.

FIG. 6 is a top view thereof; and,

FIG. 7 is a bottom view thereof.

The circular broken lines depict environment. The broken lines are for illustrative purposes only and form no part of the claimed design.
